CHRISTMAS TREE ORNAMENT OR SIMILAR ARTICLE

Alfred A. Flaster, New York, N.Y.

Application March 31, 1958, Serial No. 50,236

Term of patent 3½ years

(Cl. D29—1)

Fig. 1 is a front elevational view of a Christmas tree ornament or similar article, showing my new design;

Fig. 2 is a top plan view; and

Fig. 3 is an enlarged perspective view of the internal pendant element.

The ornamentation of all four sides of the lower portion of the ornament is identical and the undersides of the pendant element are plain and unornamented.

The stippling, except for the stippling on the sinuous support for the internal pendant elements, indicates spangles.

I claim:

The ornamental design for a Christmas tree ornament or similar article, substantially as shown and described.
